UNITED STATES PATENT OFFICE

ADRIAN S. AILES, OF CHICAGO, ILLINOIS, ASSIGNOR, BY MESNE ASSIGNMENTS, TO THE LAKE ERIE CHEMICAL COMPANY, OF CLEVELAND, OHIO, A CORPORATION OF OHIO

AUXILIARY-LOCKING MECHANISM

Application filed December 17, 1928. Serial No. 326,536.

The object of this invention is to provide an auxiliary locking mechanism for safes, vaults, and the like, which becomes effective to lock the vault or safe upon attempted 5 burglarious entry and automatically unlocks after a predetermined time interval.

Numerous other objects and advantages of the invention will be apparent as it is better understood from the following description, 10 which, taken in connection with the accompanying drawings, discloses a preferred embodiment thereof.

In the drawings:

Figure 1 is a vertical elevational view 15 showing the auxiliary locking mechanism applied to a vault door;

Fig. 2 is a side sectional elevation on an enlarged scale of the auxiliary locking mechanism;

Fig. 3 is a front sectional elevation of the same;

Fig. 4 is a top plan view of the same;

Fig. 5 is a vertical sectional elevation of the auxiliary lock controlling gearing;

Fig. 6 is a front sectional elevation of said gearing showing the parts in their normal position with the auxiliary locking mechanism in operative relationship in respect of the bolt-work of the vault;

Fig. 7 is a view similar to Fig. 6, but showing the parts applying the auxiliary locking mechanism to the bolt-work, following an attempted burglarious entry of the vault;

Figs. 8 and 9 are views similar to Fig. 6 but illustrating the operation of the controlling gearing to effect the release of the auxiliary locking mechanism in respect of the bolt-work;

Fig. 10 is a fragmentary front elevational view showing the first stage of operation of the timing device;

Fig. 11 is a sectional elevation showing the second stage of operation of the timing device;

Fig. 12 is a detailed horizontal section taken on the line 12-12 of Fig. 3;

Fig. 13 is a vertical section of the corrosive fluid vessel constituting an element of the timing mechanism;

Fig. 14 is a detailed vertical section of

the controlling rod and releasing pellet constituting parts of the timing mechanism;

Fig. 15 is a detailed vertical sectional elevation of the wire controlling mechanism, and

Fig. 16 is a vertical section on an enlarged scale taken on the line 16-16 of Fig. 15.

An ordinary vault door is shown diagrammatically at 21 in Figure 1, and the illustrative embodiment of the invention is applied to the inside of said vault door. This is one of the usual modes of application of the auxiliary locking mechanism. The vault door 21 is provided with a main locking mechanism which includes a usual combination lock contained within the box or casing 22 mounted on the inner face of the door, and controlling the operation of the bolt-work 23 which is advanced into suitable keepers in the door frame to lock the vault, and retracted to release the vault door for opening movement.

The operation of the auxiliary locking mechanism is controlled primarily by the wire which is maintained normally under tension and holds the auxiliary locking mechanism in inoperative position. On release of said tension by cutting or burning of the wire 24 or its release or disarrangement, the auxiliary locking mechanism is released.

As shown in Figure 1, the wire 24 is strung and functions up and down over the inner face of the door 21 and is supported at the top and bottom by the pulleys 25. One end 26 of the wire 24 is connected with the auxiliary locking mechanism in a manner which will appear hereinafter, and the other end 27 of said wiring is connected to a spring 28 which in turn is secured at 29 to the door 21. The spring 28 maintains the wire 24 under tension.

In the region of the combination box 22, provision is made for insuring rapid and positive severing of the wire in response to an attempted entry into the vault by punching or blowing in the combination box. The structure for effecting this result is shown in detail in Figs. 15 and 16. Secured to the inner face of the door 21, and above and below the combination box, are angle brackets

30 and 31, of which the horizontal legs 32 and 33 respectively provide support for the upper and lower ends of the hollow wire enclosing and guiding members, preferably in the form of pipes 34 and 35.

These pipes 34 and 35 have their upper and lower ends respectively mounted in holes in the horizontal legs 32 and 33 of the supporting brackets and are retained in position therein by set screws 36 screwed into sockets in the legs 32 and 33 of said brackets so as to engage the walls of the pipes 34 and 35. The pipes 34 and 35 are bent so as to extend respectively at downward and upward inclinations from the brackets 30 and 31 to the rear of the combination box 22 where their other ends are joined by a hollow connecting member 37. The wire 24 is passed through the pipes 34 and 35 and the connecting member 37, and the latter functions as a support for a wire cutting device.

Mounted horizontally in a socket in the connecting member 37 is a sleeve 38 which extends across a vertical channel 39 of said member 37 through which the wire 24 passes. The sleeve 38 is provided with a vertical hole 40 for the passage of the wire, and the wall of said sleeve at the top of the hole 40 is formed, as shown more particularly in Fig. 16, to provide a knife edge 41 for cutting the wire 24.

Within the sleeve 38 is mounted a movable shearing pin 42 provided with a vertical hole 43 for the passage of the wire 24, companion to the hole 40 of the sleeve. The upper part of the hole 43 is cylindrical in shape and closely embraces the wire 24, but at the bottom the material of the pin is cut away to provide a downwardly flared portion 44 of the hole 43 permitting the instantaneous release of the wire subsequent to the shearing operation. A screw-threaded operating pin 45 is adjustably screwed into a shouldered tube or sleeve 46 which in turn is screwed into a hole in the rear wall of the combination box 22, and the outer end of the operating pin 45 is in registry with the shearing pin 42. Upon inward movement of the combination box from punching, blowing or other dislocatory cause, the operating pin 45 engages the shearing pin 42 and moves it in the surrounding sleeve 38. This movement brings the wire 24 into contact with the knife edge 41 provided by the sleeve and effects rapid and positive cutting and disabling of the wire. After the wire is cut, the lower end which extends to the auxiliary locking mechanism is instantaneously released.

The release of the tension on the wire 24 starts into operation the auxiliary locking mechanism, whether the wire be disabled by shearing as hereinbefore described or burned or otherwise disabled so as to release its tension. The auxiliary locking mechanism is

shown more particularly in Figs. 2 to 14 inclusive and its parts are mounted within or supported by a suitable housing 47 secured to the inside of the vault door 21. Preferably the housing comprises an angle plate member 48 which is secured directly to the door and the housing proper 49 adjustably mounted on rods 50 carried by supporting blocks 51 projecting from the plate member 48. This construction permits proper adjustment of the auxiliary locking bolt with reference to the main bolt-work 23 of the vault door. One of the door-locking bolts 23 is provided with an auxiliary locking socket 52 extending transversely into said bolt and so positioned as to be in registry with an auxiliary locking bolt 53 when the main bolt-work 23 is in locked position in respect of the vault door.

The bolt 53 is mounted for axial sliding movement in a bearing socket 54 provided in the housing 49 and is in position to enter the companion auxiliary locking socket 52 in the bolt 23 to provide an auxiliary lock for preventing the opening movement of the main bolt-work. This locking operation of the bolt 53 occurs whenever tension on the wire 24 is released and prevents any door-opening operation of the main bolt-work, irrespective of impairment or destruction of the combination lock 22.

The end 26 of the wire 24 extends to and is secured within the peripheral groove 55 of a sheave 56 mounted on the outer end of a spindle 57, which extends across an upper gear chamber 58 provided within the housing 49. The spindle 57 has its bearings in the side walls of the housing 49 and rotates on an axis transverse to the axis of the auxiliary locking bolt 53. A part of the circumference of the bolt 53 is provided with annular rack teeth 59, which are adapted to mesh with companion teeth 60 of a mutilated pinion 61 fixed on the spindle 57.

The pinion 61 is rotated by a pair of coil springs 62 respectively encircling the spindle 57 on opposite sides of the pinion. One end of each spring 62 is anchored to a pin 63 set in a pin socket 64 provided in the housing 49. The other ends of the respective springs 62 abut pins 65 laterally projecting from the opposite sides of the pinion 61. The springs 62 are wound so as to be under tension when the auxiliary locking bolt 53 is in retracted position and operate, on release, to drive the pinion 61 in a counter-clockwise direction (Figs. 6 to 9 inclusive). The movement imparted to the pinion 61 by the release springs 62 through the engagement of the pinion teeth 60 with the rack teeth 59 on the bolt 53 functions to advance the bolt 53 into locking position within the socket 52 of the main bolt-work 23.

The operation of advancing the auxiliary bolt 53 into locking engagement with the bolt-work concurrently sets into action a timing

mechanism which becomes effective after a predetermined time interval automatically to withdraw the bolt 53 from its locking engagement with the bolt-work 23 and thereby permit an unlocking operation of the bolt-work. 5 Below the sheaves 56 the housing 49 is provided with an open top chamber 66, the bottom of which communicates with a chemical reaction chamber 67. A foraminous bottom plate 68 is supported by a depending flange 69 on the bottom of the chamber 66 and provides a support for a frangible vessel or cartridge 70 adapted to contain a chemically reactive liquid. The vessel or cartridge 70 10 may be constructed of any easily broken substances, such as glass, and after having been filled with the liquid is sealed to prevent its accidental escape and positioned within the chamber 66 in the manner shown, for example, in Fig. 3.

Supported in aligned bearing holes in rods 25 71 projecting horizontally from the housing 49 is a plunger 72 provided at its lower end with a head 73. Between the two supporting rods 71 the plunger is provided with a collar 74 which constitutes the bottom abutment for an encircling coil spring 75. The top of the coil spring 75 engages the under face of the top rod 71 and said spring is maintained normally compressed whereby on release it will 30 impart a vertical downward stroke to the plunger 72 so as to cause the head 73 to strike the vessel or cartridge 70 a sharp blow to break the latter and permit the escape of the fluid through the foraminous bottom 68 into the reaction chamber 67.

A detent 76 is pivoted at its lower end, as shown at 77, on the housing 49. This detent is provided with a shoulder 78 adapted to engage the bottom of the collar 74 on the plunger 72 to hold the latter normally in elevated position against the force of the spring 75. Mounted on the inner face of the detent 76 is a dolly roll 79. A spring 80, coiled around the pivot of the detent 76 and having its free end engaging the dolly roll 79, forces the detent 76 so that the shoulder 78 is held normally in engagement with the collar 74 to keep the plunger elevated, as shown in Fig. 3.

Secured to the outer face of the sheave 56 is a pin 81 which engages the dolly roll 79 on release of the sheave 56 whenever the wire 24 is disabled. The springs 62, on such release, turn the sheave 56 in a counter-clockwise direction and cause the pin 81 to engage the dolly roll 79 and turn the detent 76 so as to disengage the shoulder 78 from the abutment 74. This action releases the plunger 72 and permits the spring 75 to impart a sharp downward stroke to the plunger and cause the head 73 to fracture the vessel 70 in the chamber 66, as shown in Fig. 11. The breaking of the vessel or cartridge 70 permits the liquid contained in the cartridge to escape 60 and pass into the reaction chamber 67.

Mounted in a bore 82, extending up from the top of the reaction chamber 67, is a rod 83. This rod 83 projects upwardly so as to intercept a pin 84 projecting from the sheave 56. The movement of the sheave to cause the pin 70 81 to engage the dolly roll 79 and release the detent 66 moves the pin 84 into engagement with the top of the rod 83. This engagement of the pin 84 with the rod 83 operates to suspend further movement of the sheave 56 and 75 occurs concurrently with the end of the locking movement of the auxiliary locking bolt 53, effected by the mutilated pinion 61, as shown in Fig. 7.

The lower end of the rod 83 is of reduced diameter in respect of the main body portion of the rod and projects within the reaction chamber 67. At its extreme lower end this reduced portion of the rod is formed with a point 85 adapted to enter a socket 86 in a pellet 87. The pellet 87 is held between the pointed end 85 of the rod 83 and the upper end of a set screw 88 screwed into the chamber 67 from the bottom of the housing 49.

The pellet 87 is made of a substance which will be slowly soluble in or distinguishable by the liquid that flows into the reaction chamber 67. For example, the pellet 87 may be made of aluminum and the reactive liquid released by the breaking of the cartridge 70 90 may be a solution of caustic soda. This solution will slowly attack and dissolve the aluminum pellet 87 but will have no substantial corrosive effect on the rod 83 and the set screw 88.

The rod 83 will remain elevated sufficiently to preserve the locking relationship of the parts, by reason of the engagement of the rod with the pin 84, until the pellet 87 is substantially completely dissolved. The action 105 of the caustic soda solution on the aluminum pellet is slow and may be timed in various ways. For example, the timing may be effected by varying the strength of the solution or the size of the pellet. In order to avoid giving the burglar an opportunity to enter the vault following an unsuccessful attempt, it is desirable that the timing be so regulated as to hold the parts in position for maintaining the auxiliary locking bolt 53 in locking 110 position for a considerable period of time following an attempt by a burglar on the vault. It will be found practicable to time the solution process so that the vault remains locked over night or over a week. The gas 115 liberated in the reaction chamber 67 during the solution process may pass out of the chamber through a duct 89 to the atmosphere.

The release of the rod 83 following the action of the solution on the pellet 87 in the 125 chamber 67 permits the rod to move down into contact with the set screw 88, thereby permitting further movement of the pin 84 and the sheave 56. This sets into operation the mechanism for withdrawing the auxiliary 130

locking bolt 53 from locking engagement with the main bolt-work 23.

Referring to Figs. 5 to 9 inclusive, the pinion 61 is provided with a peripheral cut-away portion or recess 90 which, when in registry with the annular rack teeth 59 on the bolt 53, acts to disengage the pinion 61 from the bolt 53. The operation of the pinion 61 in moving the bolt 53 into the socket 52 of the main bolt-work so positions the pinion 61 with reference to the bolt 53 that only the last tooth of said pinion 61 is in engagement with the rack teeth 59. Inasmuch as the peripheral cutaway portion 90 of the pinion 61 immediately follows the last tooth, a very slight further movement of the pinion 61 in a counter-clockwise direction is sufficient to disengage the pinion from the rack tooth 59 of bolt 53. This is accomplished when the rod 83 drops in the manner hereinbefore described.

The above described disengagement of the pinion 61 from the auxiliary locking bolt 53 permits the operation of gearing for restoring the bolt 53 to retracted or unlocked position in respect of the main bolt-work 23. Mounted on a spindle 91 extending substantially parallel with the spindle 57 are located within a chamber 92 below the bolt 53 is a pinion 93, the teeth of which engage the rack teeth 59 of the bolt 53. A single spring 94 encircles the spindle 91 and has one end engaging a pin 95 projecting laterally from the pinion 93 and the other end secured to a stud 96 located in a retaining recess 97 provided at the bottom of the chamber 92. The power of the spring is such as to impart a counter-clockwise rotation to the pinion 93, as viewed in Figs. 5 to 9 inclusive, when the pinion 61 is released from engagement with the rack teeth of the locking bolt 53.

During the forward locking movement of the bolt 53, as shown in Fig. 7, the spring 94 is wound because of the rotary movement imparted to the pinion 93, the spring being less powerful than the springs 62 controlling the operation of the pinion 61. As soon as the pinion 93 is disengaged from the bolt 53 in the manner hereinbefore described, the power stored in the spring 94 will rotate the pinion 93 in the opposite direction and thereby impart a return movement to the bolt 53 so as to release it from engagement in the locking socket 52 of the main bolt-work 23, as shown in Fig. 9. A rod 98 projecting laterally from the spindle 91 and adapted to engage either the top or bottom walls of a socket 99 in the housing 49 limits the movement of the pinion 93. This rod is preferably so arranged that anyone locked in the vault may manipulate it to release the locking device after a locking operation and before the reaction time shall have expired.

As shown in Figs. 3 and 10, the sheave 56 is provided with a circumferentially-located

recess 100, which is in registry with a companion screw or pin hole 101 in the housing, when the sheave 56 is in the normal position. By inserting a screw or pin in the hole 101, when the parts are in such position, the sheave 56 may be locked against movement. This, of course, will also lock the auxiliary locking mechanism and the releasing mechanism.

With the hereinabove described construction, the auxiliary locking mechanism is released following a predetermined interval of time after the operation of the auxiliary locking mechanism. This eliminates any necessity for expensive drilling or other operations for restoring the parts to such relationship that an authorized person may open the door of the vault, and yet insures an operation of the auxiliary locking mechanism adequate to protect the vault from the burglarious attempt.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In an auxiliary locking mechanism of the class described, the combination of a locking member, actuating and releasing mechanism therefor, controlling mechanism for releasing said locking member, including a chemically reactive part which when in solution will release said locking member, and means controlled by the operation of said locking member for discharging a chemical solvent into contact with said chemically reactive part.

2. In an auxiliary locking mechanism of the class described, the combination of a locking member, actuating and releasing mechanism therefor, controlling mechanism for preventing the release of said locking member, and chemically reactive means controlled by the operation of said locking member for effecting the release of said controlling mechanism.

3. In an auxiliary locking mechanism of the class described, the combination of a locking member, actuating and releasing mechanism therefor, controlling mechanism for preventing release of said locking member, including a soluble positioning element, a frangible container for a chemically reactive fluid, means for fracturing said container to discharge said fluid concurrently with the operation of said locking member, and a fluid-containing chamber for holding said discharged fluid in contact with said soluble positioning element, whereby to release said controlling mechanism to permit

operation of said actuating and releasing mechanism and to restore said locking member to inoperative position.

4. In an auxiliary locking mechanism of the class described, the combination of a locking member, spring-operated actuating gearing therefor disengageable from said locking member, a controlling element for preventing such disengagement, timing mechanism rendered operative concurrently with the movement of said locking member to operative position and adapted at the end of a predetermined time interval to effect release of said controlling element, and other spring-operated gearing effective upon disengagement of said first-mentioned gearing to restore said locking member to inoperative position.

5. In an auxiliary locking mechanism of the class described, the combination of a locking member, actuating gearing therefor disengageable from said locking member, a controlling element for preventing such disengagement, timing mechanism rendered operative concurrently with the movement of said locking member to operative position and adapted at the end of a predetermined time interval to effect release of said controlling element, and other gearing effective upon disengagement of said first-mentioned gearing to restore said locking member to inoperative position.

6. In an auxiliary locking mechanism of the class described, the combination of a locking member, spring-operated actuating gearing therefor disengageable from said locking member, a controlling element for preventing such disengagement, a controlling element positioning device, timing mechanism rendered operative concurrently with the movement of said locking member to operative position and adapted to disable said positioning device and permit release of said controlling element, and other spring-operated gearing effective on disengagement of said first-mentioned gearing to restore said locking member to inoperative position.

7. In an auxiliary locking mechanism of the class described, the combination of a locking member, actuating gearing therefor disengageable from said locking member, a controlling element for preventing such disengagement, a controlling element positioning device, timing mechanism rendered operative concurrently with the movement of said locking member to operative position and adapted to disable said positioning device and permit release of said controlling element, and other gearing effective on disengagement of said first-mentioned gearing to restore said locking member to inoperative position.

8. In an auxiliary locking mechanism of the class described, the combination of a locking member, spring actuated gearing for ac-

tuating said locking member, said gearing acting to disengage itself from the locking member at the end of an operative cycle of the gearing, a controlling element for preventing said gearing from completing its operative cycle, a controlling element positioning device, timing mechanism rendered operative concurrently with the movement of said locking member to operative position and adapted to disable said positioning device and permit release of said controlling element, and other gearing effective at the end of the operative cycle of said first-mentioned gearing to restore said locking member to inoperative position.

9. In an auxiliary locking mechanism of the class described, the combination of a locking member, a releasing device, gearing controlled by said releasing device for actuating said locking member, a frangible container for chemically reactive fluid, a plunger released concurrently with the operation of said locking member for fracturing said container to discharge said fluid, a controlling rod for retaining said locking member in operative position, said gearing being disengageable from said locking member upon release of said controlling rod, a rod-positioning element soluble in said chemically reactive fluid and located in the region of discharge thereof, said element being adapted to release said rod upon reaction thereof in said fluid, and other gearing responsive to release of said rod for restoring said locking member to inoperative position.

10. In an auxiliary locking mechanism of the class described, the combination of a locking member, a releasing device, spring-operated gearing controlled by said releasing device for actuating said locking member, a frangible container for a chemically reactive fluid, a spring-operated plunger released concurrently with the operation of said locking member for fracturing said container to discharge said fluid, a controlling rod for retaining said locking member in operative position, said gearing being disengageable from said locking member on release of said controlling rod, a rod-positioning element soluble in said chemically reactive fluid and located in the region of discharge thereof, said element being adapted to release said rod upon its dissolving in said fluid, and other spring-operated gearing responsive to release of said rod for restoring said locking member to inoperative position.

ADRIAN S. AILES.
